(57) **CLAIM**

The ornamental design for a table, as shown and described.

DESCRIPTION

FIG. 1 is a top perspective view of an embodiment of a table; FIG. 2 is a bottom perspective view of the table shown in FIG. 1;

FIG. 3 is a top view of the table shown in FIG. 1;

FIG. 4 is a bottom view of the table shown in FIG. 1;

FIG. 5 is a front view of the table shown in FIG. 1;

FIG. 6 is a right side view of the table shown in FIG. 1;

FIG. 7 is a back view of the table shown in FIG. 1; and,

FIG. 8 is a left side view of the table shown in FIG. 1.

The broken lines are for illustrative purposes only and form no part of the claimed design.
